CLAIM

The ornamental design for an audio headset, as shown and described.

DESCRIPTION

FIG. 1 is a front perspective view of an audio headset according to the present invention;

FIG. 2 is a rear perspective view of the audio headset;

FIG. 3 is a side view of the audio headset;

FIG. 4 is an opposite side view of the audio headset;

FIG. 5 is a left side view of the audio headset;

FIG. 6 is a right side view of the audio headset;

FIG. 7 is a top view of the audio headset; and,

FIG. 8 is a bottom view of the audio headset.

The broken lines shown in the drawings represent portions of the audio headset, including an optional ear cover, that form no part of the claimed design. Specifically, the broken lines adjacent the contour surfaces represent the bounds of the claimed design while all other broken lines are directed to environment in which the design resides and forms no part of the claimed design.
